UNITED STATES PATENT OFFICE

2,676,734

GRANULATED SOAP DISPENSER

Leon W. Mertens, Fort Worth, Tex.

Application May 29, 1952, Serial No. 290,695

1 Claim. (Cl. 222—455)

1

This invention relates to dispensers for granular material and has reference to improvements in a dispenser for measuring equal amounts of granulated soap, powdered detergents and the like.

In certain washing operations, such as washing dishes, where the same amount of water is used time after time, it is apparent that a dispenser capable of repeatedly measuring and dispensing the same amount of granulated soap or the like would be desirable. However, the amount of soap desired by one user for a quantity of water differs from that of another user, and the capacity of the pan or sink of one user will also differ. It is an object of the invention to provide a dispenser of the described class capable of repeatedly dispensing equal amounts of granular material in accordance with the amounts required by the individual user.

Another object of the invention is to provide a dispenser of the character referred to having readily accessible means for regulating the repeated amounts of granular material to be dispensed.

Another object of the invention is to provide a dispenser of the character referred to capable of mass production methods, such as by injection molding methods.

A further object of the invention is to provide a unique cover which will not fall off the container when the dispenser is inverted, even though the cover is not securely attached thereto.

The invention will be more readily understood by reference to the following description and the accompanying drawing, wherein:

Figure 1 is a vertical longitudinal sectional view of a dispenser embodying the features of the invention.

Figure 2 is a sectional view of the dispenser shown in Figure 1 and showing the same in its tilted or dispensing position.

Figure 3 is a broken sectional view taken on line 3—3 of Figure 1.

Figure 4 is a broken sectional view taken on line 4—4 of Figure 3, and

Figure 5 is a broken sectional view taken on lines 5—5 of Figure 1.

The form of the invention shown includes a rectangular container 10 having front and back walls 11 and 12, side walls 13, and a bottom 14. A downwardly and outwardly projecting flange 15 may be provided around the bottom of the container 10 so as to provide an ornamental base. With reference to Figure 1, it will be noted that the end of the bottom 14 extends forwardly beyond the front wall 11, as at 16, and that an up-

2

wardly directed spout 17 is provided thereabove, and which spout includes an outwardly and angularly formed lip 18 of relatively large size.

The upper outer edges of the side walls 13 are provided with laterally projecting ribs 19 adapted to engage downwardly and inwardly formed flanges 20 on opposite sides of a cover 21. The rearward depending flange 22 of the cover 21 is straight and fits against the upper outer surface of the back wall 12, and the upper end of the front wall 11 extends above the side walls 13, as at 23, so as to provide a stop and closure for the forward end of the cover 21. A transverse rib 24 may be provided on the inner surface of the front wall 11 and arranged to frictionally engage the lower forward surface of the cover 21 for sealing the granulated contents 25 in the container 10 during the tilting operation, herein-after referred to.

Within the lower forward portion of the container, and spaced from the front wall 11, there is a vertical transverse baffle 26 which extends upwardly from the bottom 14 higher than the lower end of the front wall which is spaced from the bottom extension 16. The described front wall 11 and baffle 26 spacing provides a trap chamber 27 which is part of the construction for measuring the desired equal amounts of granular material 25 to be dispensed. The relative position of the lower end of the front wall 11 with respect to the bottom extension 16 is capable of being varied by means of vertically slideable panel 28 frictionally engaged between vertical ribs 29 on opposite sides of the spout 17 and forwardly of the front wall 11. A forwardly projecting finger grip 30 is provided on the upper end of the vertically slideable panel 28 and is accessible through the described relatively large lip 18 of the vertical spout 17.

In operation, the container 10 is filled, or partially filled, with the granular material 25 to be dispensed after adjusting the lower edge of the vertically slideable panel 28 relative to the bottom extension 16. By gravity, the granular material 25 flows into the lower end of the spout 17, and by tilting the container 10 forwardly to an inverted or nearly inverted position the material 25 in the spout 17 will be dispensed outwardly over the lip 18, as shown in Figure 2. The amount of material other than the measured amount will fall toward the inverted top 21 which is closed against spilling. By trial, the user may readily determine the proper vertical adjustment of the slideable panel 28 for measuring the amount of granular material desired, and after the same

has been determined the slidable panel is left in place for repeated operation.

The container is opened and closed by sliding the cover 21 rearwardly and forwardly, and it will be noted that the cover will remain in place throughout the tilting operation even though the same is not attached to the cover by hinges or the like.

The invention is not limited to the construction herein shown and described, but may be made in many ways within the scope of the appended claim.

What is claimed is:

A dispenser for granulated materials such as soap or the like, comprising a rectangular open top container having front, rear, and side walls together with a bottom thereacross, a removable cover over the top of said container, the lower end of said front wall being spaced from said bottom, a baffle within said container and projecting upwardly from said bottom and extending above said lower end of said front wall, said baffle being positioned inwardly of and spaced

from said front wall, an extension forming a part of said bottom and extending forwardly of said front wall, a vertical spout extending upwardly from said extension, and a vertically slidable panel shorter than the height of said container and located adjacent said front wall, means frictionally holding the sides of said slidable panel against said side walls and whereby said panel may be adapted to vary the opening thus formed between the lower end of said front wall and said bottom.
